ABSTRACT OF THE DISCLOSURE

New naphthyoxy-substituted anilides are disclosed. The compounds are useful germicidal agents. Preferred compounds contain halogen substituents.

2

Illustrative structural formulae are

4,6,4'-tribromo-2'- α -naphthyoxy-salicyanilide

2,5,4',6'-tetrabromo-2'- α -naphthyoxy-carbanilide

FIELD OF THE INVENTION

20

The present invention relates to a new class of biologically active compounds.

BACKGROUND OF THE INVENTION

25

The use of anilides as biocidal compounds is well known. In particular, the use of phenoxy-substituted anilides is well known. Thus the use of phenoxy-substituted halogenated salicylanilides as germicides is described in British Pat. No. 1,108,393, and their use as germicides and anthelmintics is described in Netherlands patent application No. 6707849. Also, the use of phenoxy-substituted carbanilides as germicides is described in J. Med. Chem., 1968, 11, 163, and their use as anti-coccidial agents is described in Australian patent application No. 46,399/64.

SUMMARY OF THE INVENTION

It has now been discovered that if an anilide contains a naphthyoxy substituent said anilide is a surprisingly effective biocidal agent. Thus it has surprisingly been found that presence of the weighty naphthyoxy group instead of the comparatively light phenoxy group gives comparable biocidal activity and in some instances more favourable activity. This is particularly true if said anilide is selected from the class of salicylanilides and carbanilides. It has been found that such naphthyoxy-substituted anilides show surprising germicidal activity. Also, they can be used advantageously in conjunction with detergents.

The scope of the invention, therefore, includes a naphthyoxy-substituted anilide in which said anilide is selected from the class consisting of salicylanilides and carbanilides. Preferably the naphthyoxy-substituent is in the aromatic ring of an aniline group in said anilide, particularly in the 2, i.e. ortho, position of said aromatic ring.

Particularly preferred compounds of the invention are naphthyoxy-substituted anilides in which said anilide is selected from the class consisting of halogen-substituted salicylanilides and carbanilides. Other substituents can be present. Preferably the halogen is chlorine or bromine and preferably the anilide contains from 1 to 3 halogen atoms.

40

An aspect of the invention is a germicidal composition

30 containing a naphthyoxy-substituted anilide according to the invention. A preferred aspect of the invention is a

35 germicidal detergent composition containing a naphthyoxy-substituted anilide according to the invention. The

detergent composition can be in any convenient form

such as liquid, paste or hard-surface cleaner but preferably

should be in the form of a toilet bar. Suitable formula-

tions for germicidal detergent compositions are given in

standard textbooks, for example in Schwartz and Perry,

Surface Active Agents.

45

A naphthyoxy-substituted anilide according to the in-

vention can be used in conjunction with other germicides,

such as 3,4,4'-trichlorocarbanilide, 3,4,4'-tribromosalicy-

anilide, 2,2'-dihydroxy-3,5,6,3',5',6'-hexachlorodiphenyl-

methane and 4,2',4'-trichloro-2-hydroxy-diphenylether.

50

A further aspect of the invention is a pharmaceutical

or veterinary composition containing a naphthyoxy-sub-

stituted anilide according to the invention together with a

pharmaceutically acceptable or veterinarianily acceptable

carrier.

55

The anilides according to the invention can be prepared

by a variety of methods. For example, one method is the

condensation of a naphthylamino-phenylether with a sali-

55 cyclic acid, the ether and the salicylic acid being prepared

by standard methods. A salicylanilide is thereby obtained.

When a halogenated salicylanilide according to the in-

vention is required, a halogenated naphthylamino-phenyl-

ether and/or a halogenated salicylic acid can be used.

An alternative method is the direct halogenation of a

naphthyoxy salicylanilide.

60

Another example of a method of preparing an anilide

according to the invention is by reaction of a naphthyl-

amino-phenylether with an aryl isocyanate, the ether and

the isocyanate being prepared by standard methods. A

carbanilide is thereby obtained. As with the salicylanil-

ides, halogenated compounds can be made by appro-

65

priate condensation or by halogenation of a naphthoxy carbanilide.

The following illustrates the preparation of intermediates that can be used in the preparation of anilides according to the invention:

(a) 2-nitrophenyl- β -naphthylether

50 gms. (0.3 mole) of β -naphthol and 13.8 gms. (0.25 mole) of potassium hydroxide were dissolved in 50 mls. of absolute alcohol. The alcohol was then removed to leave the dry potassium salt, after which 30.4 gms. (0.2 mole) of o-chloronitrobenzene were added and the mixture was heated at 140° C. for 2 hours. When cool, the mixture was extracted into chloroform and the extracts washed with 2 N sodium hydroxide and then with water. The extracts were dried over anhydrous sodium sulphate. Distillation of the residue from the chloroform extracts gave 16.0 gm. (30% of 2-nitrophenyl- β -naphthylether, B.P. 220-230° C. at 0.8-1.5 mms.

(b) 2-nitrophenyl- α -naphthylether

47.5 gms. (0.315 mole) of α -naphthol and 17.4 gms. (0.315 mole) of potassium hydroxide were dissolved in 50 mls. of absolute alcohol. The alcohol was removed, 49.7 gms. (0.315 mole) of o-chloronitrobenzene added in the cold and the mixture heated at 140° C. for 2 hours. Working up the reaction product as in section (a) above gave, in addition to a small amount of recovered o-chloronitrobenzene, B.P. 65-75° C. at 0.6 mms., 20.4 gms. (23.8%) of 2-nitrophenyl- α -naphthylether, B.P. 195-205° C. at 0.6 mm.

(c) 4-chloro-2-nitrophenyl- β -naphthylether

25 gms. (0.15 mole) of β -naphthol and 6.9 gms. (0.125 mole) of potassium hydroxide were dissolved in 50 mls. of absolute alcohol. The alcohol was removed, 19.1 gms. (0.1 mole) of 2,5-dichloronitrobenzene were added in the cold, and the mixture then heated at 140° C. for 2 hours. Working up the reaction product as in section (a) above gave 12.0 gms. (23%) of 4-chloro-2-nitrophenyl- β -naphthylether, B.P. 220-235° C. at 1-2 mms., M.P. 58-60° C. from alcohol.

(d) 2-aminophenyl- β -naphthylether

To a vigorously stirred refluxing solution of 13 gms. of zinc dust, 25 mls. of water, 75 mls. of ethanol and 8 gms. of calcium chloride was added over a half hour period 5.0 gms. (0.037 mole) of 2-nitrophenyl- β -naphthylether, and the mixture was then refluxed for a further 2 hours. The hot solution was then filtered to remove unreacted zinc. The filtrate on cooling gave 3.0 gms. (65%) of 2-aminophenyl- β -naphthylether, M.P. 73° C.

(e) 2-aminophenyl- α -naphthylether

To a stirred refluxing solution of 52 gms. of zinc dust, 100 mls. of water, 300 mls. of ethanol and 32 gms. of calcium chloride was added over a half hour period 20 gms. (0.148 mole) of 2-nitrophenyl- α -naphthylether, and the reaction mixture was stirred for a further two hours. The hot mixture was filtered to remove unreacted zinc, the filtrate diluted with water and extracted with chloroform. The chloroform extracts were dried over anhydrous sodium sulphate. Distillation of the residue from the chloroform extracts gave 16.8 gms. (89%) of 2-aminophenyl- α -naphthylether, B.P. 190-200° C. at 2.5 mms.

(f) 4-chloro-2-aminophenyl- β -naphthylether

To a stirred refluxing solution of 20 gms. of zinc dust, 150 mls. of ethanol, 50 mls. of water and 10 gms. of calcium chloride was added over a half hour period, 5.0 gms. of 4-chloro-2-nitrophenyl- β -naphthylether, and the mixture was refluxed for a further 2 hours. The hot solution was filtered to remove unreacted zinc. The filtrate on cooling gave 3.5 gms. (77.8%) of pure 4-chloro-2-aminophenyl- β -naphthylether, M.P. 121-3° C.

The following examples illustrate the preparation and biological activity of salicylanilides and carbanilides of the invention.

EXAMPLE 1

5-chloro-2'- β -naphthoxy salicylanilide

A solution of 2.0 gms. (0.0084 mole) of 2-aminophenyl- β -naphthylether, 1.45 gms. (0.0084 mole) of 5-chlorosalicylic acid and 0.5 ml. of phosphorus trichloride was stirred and refluxed for three hours. The reaction mixture was cooled, the chlorobenzene solution eluted through an alumina column using 80% chlorohexane, 18% ether and 20% acetic acid as the eluent. The fractions collected, when evaporated to dryness, gave 2.16 gms. (60%) of 5-chloro-2'- β -naphthoxy salicylanilide, M.P. 152° C. from an alcohol-water mixture.

MIC* <0.1

EXAMPLE 2

2'- β -naphthoxy salicylanilide

1.0 gms. of 2-aminophenyl- β -naphthylether, 0.58 gm. (0.0042 mole) of salicylic acid and 0.25 ml. of phosphorus trichloride in 20 mls. of chlorobenzene were refluxed for three hours. Working up the reaction product as described in Example 1 gave 0.5 gm. (32%) of 2'- β -naphthoxy salicylanilide, M.P. 118-120° C. from an alcohol-water mixture.

MIC 1-2

EXAMPLE 3

2'- α -naphthoxy salicylanilide

2.0 gms. (0.0084 mole) of 2-aminophenyl- α -naphthylether, 1.16 gms. (0.0084 mole) of salicylic acid and 0.5 mole of phosphorus trichloride were refluxed in 20 mls. of chlorobenzene for three hours. Working up the reaction product as described in Example 1 gave 1.06 gms. (35.1) of 2'- α -naphthoxy salicylanilide, M.P. 100-102° C. from 60-80 petroleum ether.

MIC 1-2

EXAMPLE 4

3,5-dichloro-2'- α -naphthoxy salicylanilide

Prepared, as described above in Example 1, from 2.0 gms. (0.0084 mole) of 2-aminophenyl- α -naphthylether, 1.74 gms. (0.0084 mole) of 3,5-dichlorosalicylic acid and 0.5 mls. of phosphorus trichloride. Recrystallisation of the product obtained gave 1.54 gms. (42.8%) of 3,5-dichloro-2'- α -naphthoxy salicylanilide, M.P. 167-170° C. from an alcohol-water mixture.

MIC 0.5-1.0

EXAMPLE 5

3,5-dichloro-2'- β -naphthoxy salicylanilide

A solution of 2.0 gms. (0.0084 mole) of 2-aminophenyl- β -naphthylether, 1.74 gms. (0.0084 mole) of 3,5-dichlorosalicylic acid and 0.5 ml. of phosphorus trichloride in 25 mls. of chlorobenzene was stirred and refluxed for three hours. The hot reaction mixture was filtered, and the filtrate evaporated to one half of its original volume in a current of dry air. The precipitated solid was filtered, washed with 60-80 petroleum ether to give 2.9 gms. (85%) of 3,5-dichloro-2'- β -naphthoxy salicylanilide, M.P. 190-191° C. from an alcohol-water mixture.

MIC 0.5-1.0

EXAMPLE 6

3,5,3'-trichloro-2'- β -naphthoxy salicylanilide

A solution of 1.5 gms. (0.005 mole) of 4-chloro-2-aminophenyl- β -naphthylether, 1.03 gms. (0.005 mole) 3,5-di-

*Minimum Inhibitory Concentration against *Staph. aureus* in parts per million.

chlorosalicylic acid and 0.25 ml. of phosphorus trichloride was refluxed in 20 mls. of chlorobenzene for three hours. Working up the reaction product as described in Example 5 gave 1.8 gms. (73.6%) of 3,5,3'-trichloro-2'- β -naphthyoxy salicylanilide, M.P. 209-10° C.

MIC<1.0

EXAMPLE 7

5-chloro-2'- α -naphthyoxy salicylanilide

A solution of 2.0 gms. (0.0084 mole) of 2-amino-phenyl- α -naphthylether 1.45 gms. (0.0084 mole) of 5-chlorosalicylic acid and 0.5 ml. of phosphorus trichloride in 20 mls. of chlorobenzene was refluxed for three hours. Working up the reaction product as described in Example 5 gave 0.85 gm. (25.6%) of 5-chloro-2'- α -naphthyoxy salicylanilide, M.P. 184-6° C. from an alcohol-water mixture.

MIC 0.1-0.5

EXAMPLE 8

3,4-dichloro-2'- β -naphthyoxy carbanilide

To a stirred solution of 1.3 gms. (0.005 mole) of 2-aminophenyl- β -naphthylether in 15 mls. chloroform was added 0.96 gm. (0.005 mole) of 3,4-dichlorophenylisocyanate, and the mixture was stirred for 3 hours. The chloroform was removed, and the residue obtained recrystallised from an alcohol-water mixture to give 1.9 gms. (90%) of 3,4-dichloro-2'- β -naphthyoxy carbanilide, M.P. 93° C.

MIC 0.1-0.5

EXAMPLE 9

3,4-dichloro-2'- α -naphthyoxy carbanilide

To a stirred solution of 2 gms. (0.0084 mole) of 2-aminophenyl- α -naphthylether in 20 mls. chloroform was added 1.58 gms. (0.0084 mole) of 3,4-dichlorophenylisocyanate, and the mixture stirred for 3½ hours. The chloroform was removed under reduced pressure, and the crude product washed twice with 60-80 petroleum ether. Recrystallisation of this solid from an alcohol-water mixture gave 1.948 gms. (54.4%) of 3,4-dichloro-2- α -naphthyoxy carbanilide, M.P. 181-3° C.

MIC 1-2

EXAMPLE 10

3,3',4-trichloro-2'- β -naphthyoxy carbanilide

To 1 gm. (0.0037 mole) of 4-chloro-2-aminophenyl- β -naphthylether in 15 mls. chloroform was added 0.7 gm.

(0.0037 mole) of 3,4-dichlorophenylisocyanate, and the reaction mixture treated as in Example 8. Recrystallisation of the crude product from an alcohol-water mixture gave 0.88 gm. (51.8%) 3,3',4-trichloro-2'- β -naphthyoxy carbanilide, M.P. 189-91°.

MIC 1-2

By way of comparison, the MIC of salicylanilide is 50.

- 10 What is claimed is:
1. A naphthyoxy-substituted salicylanilide selected from the group consisting of 2'-(alpha-naphthyoxy)-salicylanilides and 2'-(beta-naphthyoxy)-salicylanilides and wherein from 0 to 3 of the 3, 4, 5, 6, 3', 4', 5' and 6' positions of the salicylanilide may have attached thereto a chlorine atom instead of a hydrogen atom.
  2. A naphthyoxy-substituted salicylanilide according to claim 1 which is 2'-(alpha-naphthyoxy)-salicylanilide.
  3. A naphthyoxy-substituted salicylanilide according to claim 1 which is 2'-(beta-naphthyoxy)-salicylanilide.
  4. A naphthyoxy-substituted salicylanilide according to claim 1 which is substituted with 1 to 3 chlorine atoms.
  5. A naphthyoxy-substituted salicylanilide according to claim 4 which is 5-chloro-2'-(beta-naphthyoxy)-salicylanilide.
  6. A naphthyoxy-substituted salicylanilide according to claim 4 which is 3,5-dichloro-2'-(alpha-naphthyoxy)-salicylanilide.
  7. A naphthyoxy-substituted salicylanilide according to claim 4 which is 3,5-dichloro-2'-(beta-naphthyoxy)-salicylanilide.
  8. A naphthyoxy-substituted salicylanilide according to claim 4 which is 3,5,3'-trichloro-2'-(beta-naphthyoxy)-salicylanilide.
  9. A naphthyoxy-substituted salicylanilide according to claim 4 which is 5-chloro-2'-(alpha-naphthyoxy)-salicylanilide.
